(57) **CLAIM**

The ornamental design for a hand dynamo rechargeable flash light with radio alarm clock and reading lamp, as shown and described.

DESCRIPTION

FIG. 1 is a front elevation view of hand dynamo rechargeable flash light with radio alarm clock and reading lamp showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is bottom plan view thereof;

FIG. 7 is a perspective view with parts in alternative position thereof; and,

FIG. 8 is a perspective view with rechargeable handle in alternative position thereof.
